UNITED STATES PATENT OFFICE.

JOSEPH P. MONIEA, OF GLENCOE, MINNESOTA.

DESIGN FOR A PIPE-CLAMP.

52,402.

Specification for Design. Patented Sept. 10, 1918.

Application filed March 23, 1917. Serial No. 157,029. Term of patent 14 years.

To all whom it may concern:

Be it known that I, JOSEPH P. MONIEA, a citizen of the United States, residing at Glencoe, in the county of McLeod and State of Minnesota, have invented a new, original, and ornamental Design for Pipe-Clamps, of which the following is a specification, reference being had to the accompanying drawings, forming part thereof.

In the drawings—

Figure 1 is a perspective view of my improved pipe clamp, and

Fig. 2 is a side elevation of the same.

I claim:

The ornamental design for a pipe clamp, as shown.

JOSEPH P. MONIEA.
